UNITED STATES PATENT OFFICE.

ALOYS FASSL, OF WESEL, GERMANY.

ROLLING-MILL FOR ROLLING OUT HOLLOW BLOCKS.

988,868.

Specification of Letters Patent.

Patented Apr. 4, 1911.

Application filed April 10, 1908. Serial No. 426,346.

To all whom it may concern:

Be it known that I, Aloys Fassl, engineer, a citizen of the German Empire, residing at Wesel, Germany, have invented a certain 5 new and useful Rolling-Mill for Rolling Out Hollow Blocks, of which the following is a specification.

Two methods are employed for rolling out hollow blocks by means of pairs of 10 rollers arranged transversely behind each other and rotating at increasing speeds, wherein the core-bar in the first method is moved forward by the fastest rotating pair of rollers provided with grooves forming a 15 round pass, and in the second method is moved forward by the slowest pair of rollers likewise provided with round grooves. The first method necessitates a very long core-bar as the speed of the core-bar and work is 20 equal. In the second method the arrangement of the round grooved rollers at the entrance to the rolling mill offers a great disadvantage which greatly diminishes the other advantages. Interruptions in the flow 25 of the metal from one grooved roller to the other are caused by the core-bar moving forward too slowly, this having an adverse effect on uniform rolling and even makes it quite impossible. These drawbacks assert 30 themselves more particularly when soft metal is being rolled. It is therefore desirable that the core-bar should advance more rapidly than the groove of the first pair of rollers and that the grooves in said rollers 35 should be of oval shape in order to be able to stretch more readily. The advantage of a short core-bar should however be retained in order that the rolled pipe is always longer than the core-bar during the rolling. In 40 order to attain these advantages, a pair of rollers which are driven at a given speed are each provided with a semi-circular groove whereby a true round pass is formed between them. The rollers on each side of 45 these intermediate rollers are provided with semi-oval grooves, whereby an oval pass is formed between each pair of rollers. The rollers which are provided with the semi-oval grooves, are driven at variable speeds, 50 the speed of the receiving rollers, or the rollers in front of the intermediate rollers being less than the speed of the intermediate rollers, while that of the delivering rollers or the rollers in the rear of the intermediate 55 rollers is greater. The grooves in the suc-

cessive pairs of rollers on each side of the intermediate pair of rollers are increased as to their greatest diameter, whereby each successive pair of rollers will present a smaller surface which will come in contact 60 with the material being worked. The proportionate broadening of the oval pass rollers, should, as far as possible, counteract the drawing or retarding action of the core-bar and thereby prevent tearing or shortening 65 of the work from one grooved roller to the other.

In the accompanying drawings, Figure 1 is a top plan view of my invention, Fig. 2 is a side elevation of the same, Fig. 3 is a bottom plan view, Fig. 4 is a detail side elevation of one pair of the rollers having an oval pass therebetween, Fig. 5 is a detail side elevation of the intermediate pair of rollers, having a true round pass therebetween, Fig. 6 is a detail sectional view of the series of pairs of rollers with a section of the metal tubing to be rolled and the core bar or mandrel in applied position, and Fig. 7 illustrates the successive actions of the different pairs of rollers on the metal tubing.

In Figs. 1, 2, 3, 4 and 5, the approximate application of such a rolling-mill is represented. In Fig. 1, it can be seen, that all the rollers receive an increased speed of rotation 85 by the cogs *a*, *b*, *c*, *d*, *e*, *f*, *g*, as they have a decreasing diameter beginning from *a*. These cog-wheels are fixed up in the cog-wheel standards *r* and are connected with the rollers *e* by coupling and also by the bevel-wheels *m*, *n*. The rollers *o* engage 90 mutually by means of the cog-wheels *i* and *h*, in order to receive the right direction of rotation. The pair of rollers *o* on which the passes are introduced, are marked by *l*. The 95 arrangement of the horizontal rollers is especially to be seen in Fig. 4, the arrangement of the vertical rollers being shown in Fig. 5. Fig. 3 shows the horizontal rollers in section.

Fig. 6 represents the schematic arrangement of the pairs of rollers, the material *W* in the action of being rolled is shown in section, the said material *W*, as well as the mandrel *Q*, moves forward in the direction 100 of arrows.

In Fig. 7, the corresponding passes are shown, the same, with the exception of pass *o*, having oval forms. These oval passes press the material to be rolled only on a 110.

small part of the surface of the mandrel, while the round pass σ^4 encircles the mandrel closely on all sides. By this close encircling on all sides, the mandrel Q is held so firmly 5 that it can move forward only at the speed of this round pass. This speed is always greater than that of the preceding first pair of rolls, and less than that of the following last pair of rolls and is the best taken 10 from the middle pair of rolls. The intermediate pair of rollers, as has been stated heretofore, are provided with semi-circular grooves, which form a true round pass between the said rollers. The rollers on each 15 side of the intermediate rollers are provided with semi-oval grooves, whereby oval passes are formed between each of these pairs of rollers. The grooves in the successive rollers on each side of the intermediate pair of 20 rollers are increased as to their greatest diameter. Thus, the pass of the first rollers and the pass of the last rollers are the most oval, the same being able to exercise the least effect on the speed of the mandrel, so that

this moves forward at the speed of the 25 round pass.

Having thus described my invention what I claim as new and desire to secure by Letters Patent is:

The method of rolling tubes in a continuous mill from an apertured blank over a mandrel capable of movement in the direction of rolling as the same progresses, which consists in subjecting the blank when assembled on the mandrel to a rolling action in 30 said mill, and increasing the contacting area of the successive passes from the pair of rolls at the entering end of the mill, to the central pair of rolls and then decreasing the 35 contacting area of the successive passes toward the final pair of rolls, whereby the 40 speed of the mandrel is controlled by the speed of the center set of rolls.

ALOYS FASSL.
